DESIGN FOR A GLOVE

Jerome J. Fox, New York, N. Y.

Application November 23, 1936, Serial No. 66,097

Term of patent 3½ years

To all whom it may concern:

Be it known that I, Jerome J. Fox, a citizen of the United States of America, residing in Manhattan, county of New York, and State of New York, have invented a new, original, and ornamental Design for a Glove, of which the following is a specification, reference being had to the accompanying drawing, forming part thereof, wherein,

Figure 1 is a rear view of a glove showing my new design.

Figure 2 is a front view of the glove shown in Figure 1.

The glove is characterized by the combination on the glove as shown of a cuff flared in the back portion, and a central vertical seam on the back of the glove, which seam extends from the base of the fingers to a point midway from the cuff section and terminates in the step seam, as shown.

I claim:

The ornamental design for a glove, substantially as shown and described.

JEROME J. FOX.
